Des. 231,186
Patented Apr. 9, 1974

231,186

SCISSORS

Italo Marco Levi Laurenti, North Bergen, N.J. 07047

Filed June 8, 1973, Ser. No. 305,917

Term of patent 14 years

Int. Cl. D8—03

U.S. Cl. D8—57

Fig. 1.

Fig. 2.

Fig. 3.

Fig. 4.

Fig. 5.

FIG. 1 is a top perspective view of scissors showing my new design, the side opposite being identical thereto;

FIG. 2 is a top plan view;

FIG. 3 is a side elevational view;

FIG. 4 is a forward end elevational view; and

FIG. 5 is a rear end elevational view.

I claim:

The ornamental design for scissors, substantially as shown and described.
